Attorney

UNITED STATES PATENT OFFICE.

JOHN H. WERDEN, OF WINFIELD, KANSAS.

END-GATE.

SPECIFICATION forming part of Letters Patent No. 277,391, dated May 8, 1883.

Application filed January 18, 1883. (No model.)

To all whom it may concern:

Be it known that I, JOHN H. WERDEN, of Winfield, in the county of Cowley and State of Kansas, have invented certain new and useful 5 Improvements in End-Gates; and I do hereby declare the following to be a full, clear, and exact description of the invention, such as will enable others skilled in the art to which it pertains to make and use the same.

10 My invention relates to end-gates for wagons, the object being to provide an end-gate with devices of simple and durable construction adapted to securely hold the gate in place, and to clamp the side-boards of the wagon thereto.

15 The invention consists in the features of construction and combinations of parts herein-after fully described, and pointed out in the claims.

20 In the drawings, Figure 1 is an elevation of my improvement applied to a wagon, and Figs. 2 and 3 represent parts in detail.

A represents the end-gate, preferably consisting of two sections, *a* and *a'*, hinged together.

25 B represents a cleat-board rigidly secured to one section of the gate A.

C represents the ends of the side-boards of the wagon, each provided with a transverse 30 slot, *c*, to receive the ends of the clamping-bars, as shown.

D D' represent clamping-bars, the latter being arranged slightly below the former, but parallel therewith. The bar D is supported 35 upon the cleat-board by a staple, *d*, and a screw, *d'*, the latter projecting through an elongated slot of said bar. The outer end of the bar D projects through the slot *c* of the adjacent end of the side-board, and is bent at a right 40 angle to engage a catch-bar, E, secured to the outer side of said side-board. (See Fig. 2.) The inner end of the bar D is pivoted to the upper end of a lever, F. The bar D' is supported upon the cleat-board by staples *e*. The 45 inner end of said bar is pivoted to the lever F below the bar D, and its outer end projects through the slot *c* of the other side-board, and is provided with a nut, *e'*, to regulate the length of the bar. Said nut engages with the

50 lugs *g g* of a slotted plate, G, secured to the end of the side-board of the wagon. H represents a notched plate, secured to the cleat-board B for the purpose of engaging a dog, I. This dog is pivoted upon the lever F, and is connected at one end to the lever by a spiral 55 spring, *n*.

J represents an elongated staple or guard, secured to the cleat-board over the lever transversely to limit the movement thereof, and to protect the working parts of the device.

60 To securely clamp the ends of the side-boards to the end-gate, it is only necessary to turn the lever F to the right, thus drawing the clamping-bars D and D' inwardly into close contact with the catch-bar E and plate G, the dog I 65 engaging with the notched plate to lock the bars in place.

To remove the gate, the dog I is withdrawn from engagement with the notched plate, thus allowing the lever F to be turned to the left 70 to disengage the ends of the clamping-bars.

75 It will be apparent that the construction of the devices thus described is very simple and durable, and their operation easy and effective.

Having fully described my invention, what I claim as new, and desire to secure by Letters Patent, is—

1. The combination, with the end-gate and slotted side-boards, of a cleat-board and two 80 clamping-bars secured thereto, one provided with an angular end, while the other is provided with a thumb-nut, an operating-lever to which said bars are pivoted, a notched plate, and a spring-actuated dog, substantially as set 85 forth.

2. The combination, with the end-gate and slotted side-boards, the latter being provided respectively with a catch-bar, and a plate having projecting lugs, of two clamping-bars pivoted to an operating-lever, a notched plate, and a spring-dog pivoted upon said lever, substantially as set forth.

3. The combination, with the cleat-board and slotted side-boards, of a clamping-bar 95 pivoted to an operating-lever, and supported upon said cleat-board by a staple, and screw, and slot, and provided with a right-angular

outer end, of a second clamping-bar similarly pivoted to the lever and supported in staples, and provided at its outer end with a thumb-nut, a notched plate, and spring-dog, and a 5 staple or guard arranged transversely over the lever, substantially as set forth.

In testimony whereof I have signed this

specification in the presence of two subscribing witnesses.

JOHN H. WERDEN.
